HEAVY-DUTY CONTAINER FOR BULK MATERIAL

Clifford D. Fallert, St. Louis, Mo., assignor to Crown Zellerbach Corporation, San Francisco, Calif., a corporation of Nevada

Application October 8, 1956, Serial No. 614,731

1 Claim. (Cl. 229—23)

This invention relates to heavy-duty containers for packing, shipping and storing bulk commodities which require positive protection from sifting and leakage and from contamination. Containers employing this invention may be constructed of solid fibreboard, corrugated fibreboard or any other suitable material.

In the Patent No. 2,762,551, entitled "Heavy-Duty Container for Bulk Material," issued September 11, 1956, to Clifford D. Fallert, there is disclosed a heavy-duty paperboard container for packing, shipping and storing large quantities of bulk commodities, for example from about 500 to 2000 or more pounds. Paperboard containers, such as that disclosed in the above identified patent, are now being used quite extensively and have proved to be quite satisfactory.

My invention is in the nature of an improvement of the container in the above identified patent and is directed to relatively smaller quantities of bulk materials, for example, up to approximately five-hundred pounds of free flowing bulk commodities, i.e., bulk commodities in granular, pellet or powder form and often range in size up to approximately 24" x 24" x 30". Free flowing bulk commodities hereinbefore mentioned exert a substantial outward force on the walls and bottom structure of the container. Consequently, it is unexpected that containers constructed of relatively light, foldable material, such as a fibreboard and the like and without the use of exterior steel straps can be used successfully for the purposes described.

Many of the bulk materials, for example, flour, chemicals in pellet and powder form, grain and the like, have heretofore been shipped in non-collapsible, cylindrical fibre-board or metallic drums, usually having a maximum capacity of from 50 to 300 pounds depending on the density of the commodity. Containers employing the subject invention may be pre-assembled and shipped knocked-down to the user which results in substantial economies. The containers may be, and usually are, palletized so that they may be stacked two, three or even four high. Furthermore, shipping and storing space is saved and stacking ease facilitated as a result of their rectangular configuration. Other economies have resulted from their use.

More specifically, the container comprises a bottom tray with either continuous walls integral with a flat bottom panel, or an open-ended tube with bottom closure flaps, a top closure cap constructed like either type of bottom tray, the inner and outer faces of the upstanding bottom tray walls being firmly telescoped between lower end portions of inner and outer, open-ended, tubular sleeves, the bottom edges of the inner sleeve being in abutting relation with the inner face of the bottom panel of the tray. A bottom pad may be placed inside the inner sleeve and rests on the inner face of the bottom tray, the edges of said optional bottom pad being in abutting relation with the inner sleeve, and the bottom edge of the outer sleeve being in substantially coplanar relationship with the outer face of the bottom panel.

The outer sleeve terminates at its upper end a distance

2

below the top of the inner sleeve wall panels substantially equal to the height of the top cap walls. The inner sleeve has integral flaps on the upper ends of each wall panel, each flap being co-extensive with the width of the wall panel and being greater in length than the height of the top cap walls. The inner sleeve wall flaps may be folded outward and downwardly and affixed to the wall of the inner sleeve in any suitable manner before positioning the outer sleeve over the inner sleeve, but preferably the inner sleeve wall flaps are scored longitudinally at about half their width so that after the outer sleeve is telescoped and properly positioned over the inner sleeve, the described inner sleeve flaps may be angularly folded about their longitudinal scores and then readily folded downwardly in flatwise relation between the inner and outer sleeves.

The top closure cap is then telescoped over the folded inner sleeve flaps in frictionally engaging, contacting relation with the inner sleeve flaps and with the lower edges of the depending top cap wall flanges resting on the upper edge of the outer liner or sleeve.

An object of this invention is to provide an inexpensive, sift-proof and contamination-proof rigid rectangular container for quantities of bulk material up to approximately 500 pounds which will provide positive protection from contamination by extraneous matter during transportation and storage without use of exterior steel strapping.

A further object is to provide a container with flaps on the upper ends of the inner liner or sleeve and an outer liner or sleeve of reduced height, so that the flaps are insertable between the sleeves by scoring the flaps at about midway their height. The purpose being to maintain the sleeves in parallel relation, thereby preventing undesirable horizontal movement between the sleeves and to prevent the packaged material from coming into contact with free end edges of paperboard material.

A further object is to provide sift-proof containers which may vary in size, for example, up to approximately 24" x 24" x .30" or similar dimensions for shipping a wide variety of bulk commodities.

These and other objects and advantages of the invention will be apparent to those skilled in the art upon a full and complete understanding of the construction and operation of the device as hereinafter set forth.

The invention consists in the parts, arrangement and combination of parts hereinafter described and claimed. The accompanying drawings form a part of this specification and like numerals and symbols therein appearing refer to like parts wherever they occur.

Fig. 1 is a plan view of the component parts of the container embodying the preferred form of the invention;

Fig. 2 is a perspective view of a container top closure cap member shown in a partially erected condition;

Fig. 3 is a perspective view of the container top closure cap shown in Fig. 2 shown in a completely erected condition;

Fig. 4 is a perspective view of the inner liner or sleeve in completely erected condition;

Fig. 5 is a perspective view of the outer liner or sleeve in completely erected condition;

Fig. 6 is a perspective view of the preferred container bottom tray shown in a completely erected condition;

Fig. 7 is a perspective view of the pre-assembled component parts of the container in knocked-down condition embodying the preferred form of the invention;

Fig. 8 is a perspective view of the inner liner or sleeve telescoped into the bottom tray and the optional bottom pad being positioned downwardly inside the inner liner or sleeve;

Fig. 9 is a perspective view of the outside liner or sleeve telescoped over the inside liner and bottom tray;

Fig. 10 is a perspective view of the inner liner or sleeve flaps in the preferred form being folded downwardly and inside the outer liner about the horizontal score positioned about midway their height;

Fig. 11 is a perspective view showing the flaps of the inner liner or sleeve completely positioned inside the outer liner or sleeve;

Fig. 12 is a perspective view of the container completely assembled;

Fig. 13 is a sectional view of the assembled box taken along lines 13—13 in Fig. 12; and

Fig. 14 is a sectional view showing the alternate bottom tray constructed like the top closure cap 20.

The top closure cap 20, shown in Fig. 1, is provided with a top panel 21 defined by score lines 22 which also define in part the hinge connection of the triangular connecting flaps 23 and the wall flanges 24. Diagonal slots 25 also define in part the triangular flaps 23. Diagonal score lines 26 in the wall flanges 24 are provided in order that the cap may be collapsed in the assembled condition.

The inner liner or sleeve 27, shown in Fig. 1, is provided with four side panels 28 defined by three score lines 29 and score line 30 which also define in part the hinge connection of the upper flaps 31. Side slots 32 define the side margins of the upper flaps 31. Score lines 33 are positioned, in the preferred form of the invention, midway the heights of the upper flaps 31.

The outer liner or sleeve 34, shown in Fig. 1, is provided with four side panels 35 defined by three score lines 36.

The optional bottom pad 37 is shown in Fig. 1.

The bottom tray 38, shown in Fig. 1, is provided with four side panels 39 defined by three score lines 40 and score line 41 which also define in part the hinge connection of the bottom closure flaps 42. Side slots 43 define the side margins of the bottom closure flaps 42.

The top closure cap 20 may be erected in any desired manner, however, a preferred method of erecting the blank is to affix staples 44 through the triangular flaps 23 and wall panels 24 which are in juxtaposed relation as shown in Fig. 2.

A preferred method of erecting the inner liner or sleeve blank 27 is to affix a tape 45 to the outside of the two free edges of the side panels 28, as shown in Fig. 4.

A preferred method of erecting the outer liner or sleeve blank 34 is to affix a tape 46 to the outside of the two free edges of the side panels 35, as shown in Fig. 5.

The bottom tray 38 may be erected in any desired manner, however, a preferred method of erecting the blank is to fold the side panels 39 right angularly about the score lines 40 affixing a tape 47 to the outside of the two free side edges of the side panels 39. The bottom closure flaps 42 are folded up and adhesively secured together in any suitable manner, as shown in Fig. 6.

Each of the pre-assembled component parts of the container may be collapsed for economical shipment to the user, as shown in Fig. 7.

The optional bottom pad 37 is being positioned inside the inner liner or sleeve 27 which has been telescoped inside the bottom tray 38, as shown in Fig. 8.

The outer liner or sleeve 34 is telescoped over both the inner liner or sleeve 27 and the bottom tray 38, as shown in Fig. 9.

The upper flaps 31 of the inner liner on sleeve 27 are folded down about score lines 30 and are folded into an L-shape about the score lines 33 with their free end edges resting on the upper end of the outer liner or sleeve 34. The flaps 31 can then be readily forced downwardly into flatwise relation between the inner liner or sleeve 27 and the outer liner or sleeve 34, to prevent undesirable horizontal movement and removing free end edges of paperboard from the container's interior surface thereby pro-

viding positive protection of contents from sifting and from contamination, as shown in Fig. 10.

The top closure cap 20 is telescoped over the inner liner or sleeve 27 into contact with the free upper edge of the outer liner or sleeve 34. The upper flaps 31 of the inner liner or sleeve 27 are then in juxtaposed relation with the inner face to the top cap wall panel 24, thus completing the assembly of the container, as shown in Fig. 12.

The pre-assembled container may be set up in any desired manner, however, a preferred method is to set up the container on any type of pallet or skid for handling ease. The bottom tray 38, in its erected condition, is then placed on the upper face of such skid. The inner liner or sleeve 27 is telescoped inside the bottom tray. The optional bottom pad 37 may then be placed inside the inner liner or sleeve 27 resting on the upper face of the bottom tray closure flaps 42. The outer liner or sleeve 34 is telescoped outside both the inner liner or sleeve 27 and the bottom tray 38 with its lower free end edges coplanar with the bottom face of the tray.

The upper flaps 31 of the inner liner or sleeve are then folded down between the inner liner or sleeve 27 and the outer liner or sleeve 34 as hereinbefore described to maintain the sleeves in parallel relation thereby preventing undesirable horizontal movement and to prevent the packaged material from sifting and coming into contact with free end edges of paperboard material. The container may then be filled with bulk material in granular, pellet or powder form and the top closure cap 20 telescoped over the inner liner or sleeve flaps 31 with the inner marginal edge portions of the flat top panel 21 resting on the broad smooth upper edge fold 30 of the inner sleeve, completing the set up of the container.

It is to be understood that the embodiments herein described are illustrative and not restrictive, and it is also to be understood that the invention may be susceptible of embodiment in other modified forms, and that all such modifications which are similar or equivalent hereto come equally within the scope of the claim next appearing.

What I claim is:

A collapsible sift-proof rectangular paper board container free of external projections for storing and shipping materials in powder, pellet, granular and other flowable forms wherein said materials are effectively protected from contamination by contact with exposed raw edges of paper board, said container comprising a bottom tray including in-folded bottom closure flaps and upstanding side panels extending substantially normally to said bottom closure flaps, an inner sleeve including a plurality of side walls, said side walls being in abutting relationship with the inner faces of adjacent side panels of the bottom tray, the lower free end edges of the inner sleeve being in abutment with inner surfaces of the bottom closure flaps of the bottom tray, an outer sleeve disposed in telescoping relationship with said inner sleeve, said outer sleeve having a plurality of side walls, said side walls being in abutting relationship with the outer surfaces of the adjacent side panels of the bottom tray, the lower free end edges of the outer sleeve being in coplanar relationship to outer surfaces of the bottom closure flaps of the bottom tray, each of the side walls of said inner sleeve including at the upper end thereof a flap formed integral therewith and defined by a score line, the upper free end edge of each wall of the outer sleeve being spaced from said score line of the adjacent wall of the inner sleeve in the direction of said bottom tray, said flaps on the inner sleeve being folded over with the free ends thereof extending between and abutting the outer surface of the associated wall of the inner sleeve and the inner surface of the associated wall of the outer sleeve, and a top closure cap, said top closure cap including a top panel and depending wall flanges formed integral therewith, said top closure cap being

telescoped over said inner sleeve flaps such that the free end edges of said wall flanges of the top closure cap are in abutment with the free upper edges of the outer sleeve, the inner faces of said wall flanges of the top closure cap being in abutment with the outer faces of the adjacent flaps, and the folds formed by the flaps at the top of the inner sleeve being in abutment with the inner face of the top panel of the top closure cap.
